UNITED STATES PATENT AND TRADEMARK OFFICE
CERTIFICATE OF CORRECTION

PATENT NO. : D814,893 S
APPLICATION NO. : 29/557558
DATED : April 10, 2018
INVENTOR(S) : George E. Alliss

Page 1 of 1

It is certified that error appears in the above-identified patent and that said Letters Patent is hereby corrected as shown below:

This certificate supersedes the Certificate of Correction issued on September 7, 2021. The certificate which issued on September 7, 2021 is vacated because the certificate issued without proper approval of Petition 37 CFR 1.78 requested correction to item (63) Related U.S. Application Data of Patent No. Des.814,893 S. The Certificate of Correction which issued September 7, 2021 was published in error and should not have been for this patent.

Signed and Sealed this
Sixth Day of September, 2022
Katherine Kelly Vidal
Director of the United States Patent and Trademark Office
